UNITED STATES PATENT OFFICE.

FRANCES S. LAROCHE, OF SAN FRANCISCO, CALIFORNIA.

HAT-FASTENER.

1,084,282.

Specification of Letters Patent. Patented Jan. 13, 1914.

Application filed June 29, 1912. Serial No. 706,628.

To all whom it may concern:

Be it known that I, FRANCES S. LAROCHE, citizen of the United States, residing in the city and county of San Francisco and State 5 of California, have invented new and useful Improvements in Hat-Fasteners, of which the following is a specification.

This invention relates to means for holding on hats without the use of the ordinary 10 dangerously long hat-pin.

The invention consists of the parts and the combination and construction of parts as hereinafter more fully described and claimed, having reference to the accompanying drawings, in which—

Figure 1 is a perspective view showing the application of the device. Fig. 2 is a perspective view showing the application to a barrette. Fig. 3 shows a single flexible hat-pin.

A represents a hat which is provided with suitable eyelets or gromets 2 in the sides, through which a specially designed hat pin or two hat pins may be passed.

In Fig. 2 there is shown a single hat pin consisting of a thin flexible band 3, of steel or other suitable material, which extends across the front of the hat in decorative fashion, with the flexible ends of the band pin passing through the eyelets 2 and through the hair, and the ends brought together and crossed at the back of the hair and buttoned to little studs 4, on the usual barrette or comb 5, worn at the back; the 25 flexible ends of the steel or celluloid band pin 3 being provided with button-holes 6. The crossed ends of the hat pin or hat pins are then engaged behind a guard 7, formed on or carried by the barrette 5. Fig. 3

shows a single flexible hat-pin, in which case 40 two are used, one on each side of the hat, the ends being brought together, buttoned and crossed, as shown in Fig. 2.

Having thus described my invention, what I claim and desire to secure by Letters Patent is—

1. The combination with a hat having eyelets in either side, a flexible band pin passing through said eyelets, said band pin provided with perforations in its length, a barrette having studs engageable in said perforations, and said barrette having a guard with which the end portion of the pin may be engaged.

2. The combination with a hat having eyelets at opposite sides, of a hat pin of band-form crossing the front of the hat and having flexible ends one of which passes through each of said eyelets, said ends having a series of perforations, a barrette having studs 55 engageable in said perforations, and a guard on the barrette behind which the free ends of the pin may be engaged.

3. The combination with a hat having eyelets in either side, of a hat fastener comprising a flexible pin adapted to pass through one of said eyelets and provided with perforations in its length, and a barrette, having a stud engageable in said perforations, said barrette having a guard with which the 60 end portion of the pin may be engaged.

In testimony whereof I have hereunto set my hand in the presence of two subscribing witnesses.

FRANCES S. LAROCHE.
